Application May 19, 1953, Serial No. 356,022

4 Claims. (Cl. 155—179)

This invention relates generally to seat structures and more particularly to a new and improved mounting for a seat or platform adapted to absorb shocks or stresses and provide resiliency in both the vertical and horizontal directions.

The prior art structures can generally be classified in two categories, one providing a relatively rigid surface and the other a resilient cushion-type surface. Past experience has shown that the resilient cushion-type is more comfortable for the user while a properly formed relatively rigid seating surface is the most healthful for prolonged use. Either of these types of seating structures may or may not be covered with a variety of upholstery and padding but generally speaking all seats fit into one or the other of these basic categories.

In some cases seating structures have utilized a flexible framework stretched over a rigid frame in an attempt to provide a seat incorporating the benefits of both of the classifications mentioned above. However, in such cases little or no deflection is provided in the frame so that a high circumference surrounding the seating area results. This, of course, is undesirable from both a comfort and health standpoint. In order to eliminate all of the disadvantages of the prior seat arrangements and to provide a seat structure which is both healthful and comfortable this invention incorporates a flexible framework on which the seating surface itself is supported. Such a resilient or flexible framework, of course, must provide a certain amount of horizontal and vertical support. However, it has been found that a structure according to this invention provides not only vertical flexibility but a limited amount of horizontal flexibility in all directions.

It is an important object of this invention to provide a seat structure which resiliently supports the seating surface and provides both vertical and horizontal flexibility.

It is another object of this invention to provide a seat mounting structure which reduces the fatigue of the user by firmly supporting while still being comfortable and restful.

It is a still further object of this invention to provide a seat structure which is adapted to simple and economical manufacturing techniques so as to reduce the cost of structure.

The foregoing and other objects and advantages will become apparent in view of the following description taken in conjunction with the drawings, wherein:

Fig. 1 is a front view of a seat structure incorporating this invention wherein the seat portion is supported by a separate support portion;

Fig. 2 is a side view of the seat structure shown in Fig. 1;

Fig. 3 is a plan view of a seat structure incorporating this invention wherein a substantially rectangular shape is provided;

Fig. 4 is a plan view similar to Fig. 3 excepting a generally circular seat structure is provided;

Fig. 5 is a cross sectional view of the seat structure shown in Fig. 2;

2

Fig. 6 is a cross sectional view showing a seat structure according to this invention which is subjected to a concentrated off-center load;

Fig. 7 is a cross sectional view of a seat structure according to this invention employing an integral platform structure; and,

Fig. 8 shows another embodiment of this invention wherein the support section is formed with a generally tubular structure.

10 A seat structure according to this invention comprises a spring device generally ring shaped formed of resilient material. The spring device includes an upper portion providing a substantially horizontal surface adapted to engage and support the circumference of a seating surface, a downwardly extending portion and a lower portion beneath and spaced from the upper portion.

15 In a preferred embodiment of this invention the seat structure is formed with a substantially horizontal seating platform or surface which is mounted at its periphery on a support member. The support member provides a surface adapted to engage and support the periphery of the platform and is formed with a downwardly extending section. This downwardly extending section extends completely around the support section of the support member and terminates in an inwardly extending mounting section. The support section, the downwardly extending section and the mounting section combine to form a ringlike support member which is completely enclosed and which has a cross section substantially in the shape of a C. In the preferred embodiment the platform or seating surface is formed of a relatively rigid sheet material which may be formed with contours adapted to provide a comfortable seat arrangement and the support member is formed of molded or stamped resilient sheet material which provides a spring action. The lower or inwardly extending surface of the support member may be adapted to any suitable frame or base.

20 Referring to the drawings, Fig. 1 discloses a preferred embodiment of this invention wherein the seat or platform portion 10 is formed of relatively rigid sheet material which may be formed with contours best seen in Fig. 1 adapted to provide a comfortable seating surface. The platform portion 10 is attached at its periphery to a support member 11 which extends completely around the platform in the form of a ring. The support member 11 is formed with a generally horizontal upper portion 12 which engages and supports the platform 10, a downwardly extending portion 13 and an inwardly extending bottom portion 14. These three portions of the support member form a substantially C-shaped resilient support which extends completely around the platform 10 and provides a resilient spring-like support for the platform which permits vertical and horizontal movement of the platform and combinations thereof. Bolt or fastening devices 16 are provided in the lower inwardly extending portion 14 so that the support member may be fastened to the base of the furniture.

25

30 The support member 11 is preferably formed of a sheet material which may be molded to the desired shape and which provides resilient properties. Numerous plastic materials satisfy these requirements and may be utilized and, if desired, even sheet metal is satisfactory. The choice of material, the thickness of the sheet and the dimensions of the support member may be varied to provide the desired strength and spring characteristics. If a stiff structure is desired the thickness of the sheet material may be increased. The overall height of the support member may be changed to provide different spring characteristics.

35 Figs. 3 and 4 disclose two different forms of a structure according to this invention and other outside shapes may be provided if desired for particular applications. In

some applications it may be desirable to form the platform 10 integrally with the support member 11 as shown in Fig. 7.

When the load is applied uniformly the support member 11 is compressed substantially uniformly resulting in a vertical spring action which will absorb shocks and the like. However, in some cases a non-uniform load will be applied to the seat structure and, in such cases, the platform will tend to tip in the direction of the load as shown in Fig. 6. This results in an action somewhat like the swivel seat without requiring the elaborate swivel structure present in past devices. As noted in Fig. 6 the portion of the member adjacent to the concentrated stress is compressed tending to cause the platform to move slightly in the direction of the off-center load or stress. This results in a raising of the opposite side caused by a straightening of the support member in that section. The platform or seat is thus tilted relieving the person using the seat of uncomfortable and unhealthy strains which were present in the prior structures. Those skilled in the art will realize that a seat structure incorporating this invention has the advantages of a relatively firm support while providing the comfort normally only present in a soft cushion.

If desired the structure according to this invention may be upholstered or covered with pads to provide any desired appearances without departing from the invention. It is apparent that although the seat structure according to this invention has the advantages normally present only in soft cushions that the cost of manufacture is decidedly reduced since the structure may be molded as one piece with the platform formed integrally with the support member as shown in Fig. 7, or in two pieces which may easily be attached. All of the expensive and time consuming operations of spring and framing assembly are eliminated thus providing not only a more satisfactory seating device but reducing the manufacturing cost tremendously.

The fabricated seat construction illustrated in Fig. 8 comprises a seating surface member 18 which is generally circular in plan view and which is of thickness approximating that of the seating surface portions of the devices of this invention illustrated in the other drawings herein and described above. This fabricated seat 10 also includes a spring element 19 in the form of a torus of resilient material. The seat element 18 is secured around its periphery to the top of the torus spring 19 and the lowermost annular portion of the torus spring is disposed for engagement over substantially 360° with an annular supporting surface.

Having completed a detailed description of a preferred embodiment of the present invention so that others skilled in the art may be able to understand and practice the same, we state that what we desire to secure by Letters Patent is not limited by said preferred embodiment but rather is defined in what is claimed.

What is claimed is:

1. A seat combining universal spring support and balanced horizontal and vertical resiliency which comprises a seating surface member having a central load-bearing

area and an outer substantially continuous edge portion, and an annular spring element secured to the said member substantially continuously along the entire length of said edge portion, said spring element having an annular portion disposed below the seating surface member and within the edge portion thereof for engagement over substantially 360° with an annular supporting surface.

2. A seat combining universal spring support and balanced horizontal and vertical resiliency which comprises

10 a seating surface member having a central load-bearing area and an outer substantially continuous edge portion, and an annular spring element secured to the said member substantially continuously along the entire length of said edge portion, said spring element having an annular inwardly-directed portion below the seating surface member and terminating in an edge disposed within the edge portion of said member for engagement over substantially 360° with an annular supporting surface.

3. A fabricated seat combining universal spring support and balanced horizontal and vertical resiliency which

20 comprises a seating surface member having a central load-bearing area and an outer substantially continuous circular edge portion, and a separately-formed closed, ring-shaped, tubular spring element of resilient sheet material secured to the said member substantially continuously along the entire length of said edge portion, said spring element being disposed below the seating surface member and having an annular lower surface portion for engagement over substantially 360° with an annular supporting surface.

4. A fabricated seat combining universal spring support and balanced horizontal and vertical resiliency which

25 comprises a seating surface member having a central load-bearing area and an outer substantially continuous edge portion, and a separately-formed annular spring element secured to the said member substantially continuously along the entire length of said edge portion, said spring element having an annular edge portion spaced below the seating surface member and disposed within and substantially paralleling the edge portion of the said member for engagement over substantially 360° with an annular supporting surface.
